Primary Examiner — Andrew Kerr

Assistant Examiner — Chariton Alexakis

(57) CLAIM

The ornamental design for a decanter box for spirits as shown and described.

DESCRIPTION

The patent or application file contains at least one drawing executed in color. Copies of this patent or patent application publication with color drawing(s) will be provided by the Office upon request and payment of the necessary fee.

1.1: Front

1.2: Back

1.3: Oblique view

1.4: Profile view

1.5: Top

1.6: Bottom

1.7: Open box

Decanter box for spirits comprising two sides encapsulating the decanter, which opens in the middle using a press stud on the edge of the box; the inside of each side is hollowed out and outlines the shape of the carafe, also visibly from the outside.

1 Claim, 7 Drawing Sheets
